UNITED STATES PATENT OFFICE.

DANIEL ARTHUR QUIGGIN, OF BLUNDELL SANDS, NEAR LIVERPOOL, AS-SIGNOR OF ONE-HALF TO JOHN NEWTON, OF LONDON, ENGLAND.

APPARATUS FOR EVAPORATING SEA OR OTHER WATER.

SPECIFICATION forming part of Letters Patent No. 448,542, dated March 17, 1891.

Application filed June 6, 1890. Serial No. 354,442. (No model.) Patented in England January 11, 1889, No. 538, and May 16, 1889, No. 8,139.

To all whom it may concern:

Be it known that I, DANIEL ARTHUR QUIGGIN, a subject of the Queen of Great Britain, residing in Blundell Sands, near Liverpool, in the county of Lancaster, England, have invented certain new and useful Improvements in Apparatus for Evaporating Sea or other Water for Obtaining a Supply of Fresh Water, (for which I have obtained Letters Patent in Great Britain, dated January 11 and May 16, 1889, and numbered 538 and 8,139, respectively,) of which the following is a specification.

My invention relates to that class of apparatus in which the sea or other water to be evaporated in order to obtain a supply of fresh water is heated by passing steam through heat-transmitting surfaces immersed therein, the steam (which I shall hereinafter term "primary steam") being condensed or partially condensed thereby. The vapor from the sea or other water, which will be subsequently referred to as "secondary vapor," may be led to a condenser and so form fresh water. Where the apparatus is fitted on board ship, the main condenser of the engines is generally utilized, and the fresh water so formed is used as "feed make up" for the boilers. In most cases, however, instead of leading the secondary vapor to a condenser, it is found more convenient and economical to lead it or a portion of it through the heat-transmitting surfaces of a second evaporator similar to the first, in which it is condensed and gives up its heat to the sea or other water in the said second evaporator. The vapor so produced in the second evaporator, which I term "tertiary vapor," is led to a condenser, or it may be led to the heat-transmitting surfaces of a third evaporator, and so on for a series of evaporators, the vapor produced in the last evaporator of the series being led to a condenser. According to my present invention I pass the partially-condensed primary steam after it has left the first evaporator through heat-transmitting surfaces in a feed-heater, in which it serves to heat the sea or other water used for feeding the several evaporators and is itself thereby wholly condensed and cooled. When a num-

ber of evaporators are used in series, I feed them all from the one feed-heater, a feed-box being interposed, in which there is a separate feed-valve for each evaporator, said feed-valves being, if necessary, differentially loaded to suit the different pressures in the several evaporators. 55

The heat-transmitting surfaces used in my present invention are preferably constructed as described in the specification and drawings lodged by me with an application dated May 1, 1890, for a patent, Serial No. 350,165.

In order that my invention may be readily understood, reference is made to the accompanying drawings, in which two evaporators are shown in series, together with a feed-heater and feed-box.

Figure I shows the apparatus in elevation, one of the evaporators, which are similar, being in section on the line A A of Fig. II. The evaporators are shown farther apart than usual in order that the connections may be indicated more clearly. Fig. II is a plan of the apparatus, one of the evaporators being in section on the line B B of Fig. I, the baffle-plate 14 being removed. Fig. III is an end elevation, the feed-heater and feed-box being in section on the lines C C of Fig. II; and Fig. IV is a section through the feed-box on the line D D of Fig. III. 75 80

Throughout the drawings similar parts are indicated by the same reference-figures, and in the case of sections the direction in which they are viewed is indicated by the small arrows placed adjacent to the letters denoting the plane of section. 85

The evaporators consist each of an upright cylindrical shell 1, having dished ends, forming the top 2 and bottom 3. The ends are strengthened by a stay-bar 4, which is secured to each and is prolonged through the bottom and serves as a holding-down bolt 5, by means of which the evaporator is secured to its seating 6. The primary steam enters by the pipe 7 and inlet-valve 8 to the inlet-pipe 9. The inlet-pipe is circular in plan and has a number of unions, to which are attached the heat-transmitting surfaces 10, which consist of helical coils of crescent-shaped cross-section constructed in accordance with my specifica- 95 100

tion aforementioned. The lower ends of these coils are attached to unions on a condensed steam-outlet pipe 11, similar to the steam-inlet pipe. The partially-condensed steam leaves the evaporator by the pipe 12 and passes into the feed-heater. The secondary vapor leaves the evaporator by the vapor-outlet 13. This outlet is designed to prevent any of the water in the evaporator leaving with the vapor as a result of priming. Over the outlet is held a cup 13^a. Water trapped in the outlet drains back into the evaporator by the holes 36 in the pan 13^b. Priming is also prevented or mitigated by the baffle-plate 14. The secondary vapor is led from the first evaporator to the heating-surfaces of the second evaporator by the pipe 15, and after passing through the said heating-surfaces it leaves the evaporator by the outlet-pipe 16. Where it is not desired to pass the whole of the secondary vapor through the heating-surfaces in the second evaporator, a portion is led through the pass-by pipe 17. This pipe 17 is led into the outlet-pipe 16 after the manner of an ejector-nozzle, so as to draw the secondary vapor through the heating-surfaces. The secondary vapor, which leaves the apparatus by the pipe 16, and the tertiary vapor, which leaves by the outlet-pipe 46, when condensed and cooled, form potable water.

The evaporators are fitted with man-hole doors 18 and blow-off cocks 19. The usual mountings, such as safety-valves and pressure and water gages, are also fitted, but are not shown in the drawings.

Referring now to the arrangement for supplying and heating the feed-water, which is illustrated in Figs. III and IV, the feed-heater consists of a cylindrical shell 37, with detachable ends 38, to which the heating-surfaces 39 are attached, these latter being in communication through their ends with the inlet-pipe 12 and outlet-pipe 40. The partially-condensed primary steam, as before mentioned, enters the heating-surfaces 39 of the feed-heater by the pipe 12, is wholly condensed therein, and leaves the feed-heater as fresh but not potable water by the outlet 40, and is generally returned to the boiler. The feed-box 20 is rectangular in shape and is divided into two chambers 21 and 22, which supply the first and second evaporators, respectively. The feed-water enters the feed-heater by the inlet 23, and, after being heated by passing round the heating-surfaces 39, it passes by the two pipes 24 and 25 into the chambers 21 and 22. Each of these latter chambers is connected to its evaporator by a steam-pipe 26 and water-pipe 27, so that the water-level in each chamber is the same as that in the evaporator to which it is connected. The feed-water enters the chambers 21 and 22 by the valves 28 and 29, which are controlled by the floats 30 and 31. The valves are loaded by the weights 32 and 33. The floats are carried on bell-crank levers 34, fulcrumed at 35 and connected to the valves by

links 41. The link and short arm of the lever form a toggle-joint, which, as the float rises, operates to shut the valve. The adjustable screws 42 limit the lift of the valves. The amount by which the valve is opened for any given water-level is determined by the position of the valve-seating 43 relatively to the fulcrum 35. The valve-seating is screwed externally, and its position relatively to the fulcrum is adjusted by turning it by means of the hexagon head 44. It is secured in the proper position by the check-nut 45. The pipes 24 and 25 are attached to the seatings 80 of the valves 28 and 29 by unions. In this way the evaporators are fed from a common supply and the level of the water kept constant in each, although the pressures in each may be different. Where the water to be evaporated is sea-water a quantity must from time to time be blown out through the blow-off cocks 19 to keep the degree of saturation within the required limit.

Although I find it convenient to use tubular helical coils of crescent-shaped cross-section constructed according to my prior specification before mentioned as heat-transmitting surfaces in my present invention, I do not confine myself to the use of such coils.

Having now fully described my invention, what I claim, and desire to secure by Letters Patent, is—

1. In combination, in an evaporator apparatus, the evaporator-chamber having a heating-surface therein, the feed-water heater, also having a heating-surface, a pipe 12, connecting the heating-surface of the evaporator with that of the feed-water heater, and a conduit-pipe 24, leading from the water-chamber of the feed-water heater, said pipe communicating with the water-chamber of the evaporator, substantially as described.

2. In combination, the series of evaporators, a feed-water heater having water-pipes leading to the several evaporators, means for separately controlling the flow of water through said pipes, and a steam-pipe leading from the coil of the first evaporator to the heating-surface of the feed-water heater, substantially as described.

3. In apparatus for evaporating sea or other water for obtaining a supply of fresh water, the combination of two or more evaporators in series, the heat-transmitting surfaces of the second and each succeeding evaporator being connected to the vapor-outlet of the evaporator immediately preceding it, a feed-heater the heating-surfaces of which are connected to the condensed primary steam-outlet pipe of the first evaporator, and a feed-box having as many chambers as there are evaporators, each chamber being connected to its evaporator by leveling-pipes and receiving the heated feed-water from the feed-heater by a pipe which communicates with the chamber through a valve controlled by a float in said chamber, the said valves being differentially loaded to suit the different pressures in

the several evaporators, substantially as described.

4. In apparatus for evaporating sea or other water for obtaining a supply of fresh water, in combination with a series of evaporators, a feed-box having as many chambers as there are evaporators, each chamber being connected to its evaporator by leveling-pipes and communicating with the feed-supply by means of a valve controlled by a float in said chamber, said valves being, if necessary, differentially loaded to suit the different pressures in the several evaporators, substantially as described.
- 15 5. In apparatus for evaporating sea or other water for obtaining a supply of fresh water, in combination, a feed-box 20, a feed-valve controlled by a float which is attached to one arm of a bell-crank lever, the other arm of 20 the lever and a link connecting it to the valve forming a toggle-joint by means of which the valve is operated, and a valve-seating 43, ad-

justable through the wall of the box from the outside in position relatively to the fulcrum of said bell-crank lever, substantially as described.

6. In apparatus for evaporating sea or other water for obtaining a supply of fresh water, in combination with the vapor-inlet pipe and condensed-vapor-outlet pipe, a pass-by pipe 30 forming a branch of the inlet-pipe, through which a portion of the vapor passes instead of passing through the heating-surfaces, said pass-by pipe being led into the condensed-vapor-outlet pipe after the manner of an 35 ejector, substantially as described.

In testimony whereof I have hereunto set my hand in the presence of two subscribing witnesses.

DANIEL ARTHUR QUIGGIN.
